UNITED STATES PATENT OFFICE.

DONALD L. BENTON, OF LOS ANGELES, CALIFORNIA, ASSIGNOR TO AMERICAN CHAIN COMPANY, INC., OF BRIDGEPORT, CONNECTICUT, A CORPORATION OF NEW YORK.

DESIGN FOR A BUMPER.

Application filed December 7, 1925. Serial No. 15,671. Term of patent 14 years.

To all whom it may concern:

Be it known that I, DONALD L. BENTON, a citizen of the United States, residing at the city of Los Angeles, county of Los Angeles, State of California, have invented a new, original, and ornamental Design for a Bumper, of which the following is a specification, reference being had to the accompanying drawings, forming part thereof.

The figure is a perspective view of a bumper, showing my new design.

I claim:

The ornamental design for a bumper as shown.

DONALD L. BENTON.
